INFLATABLE TOURNIQUET

Henry G. Meyer, 63 Briarcliff Road,
Hillsdale, N.J. 07642

Filed May 19, 1966, Ser. No. 2,357

Term of patent 14 years

(Cl. D83—1)

FIG. 1

FIG. 2

FIG. 3

FIG. 4

FIG. 1 is a view from one side of an inflatable tourniquet embodying my design;

FIG. 2 is a view thereof from the remaining side;

FIG. 3 is a perspective view thereof with the bladder receiving compartment opened and portions projecting therefrom; and

FIG. 4 is a sectional view taken along the line 4—4 in the direction of the arrows as seen in FIG. 1.

I claim:

The ornamental design for an inflatable tourniquet, substantially as shown.
